(57) **CLAIM**

The ornamental design for a dental implant applied to cranial fossa and minimally invasive plate, as shown and described.

DESCRIPTION

FIG. 1 is a perspective view of an embodiment of the present design;

FIG. 2 is a front view of the embodiment of FIG. 1 of the present design;

FIG. 3 is a rear view of the embodiment of FIG. 1 of the present design;

FIG. 4 is a right side view of the embodiment of FIG. 1 of the present design;

FIG. 5 is a left side view of the embodiment of FIG. 1 of the present design;

FIG. 6 is a top view of the embodiment of FIG. 1 of the present design;

FIG. 7 is a bottom view of the embodiment of FIG. 1 of the present design;

FIG. 8 is a perspective view of an alternative embodiment of the present design;

FIG. 9 is a front view of the embodiment of FIG. 8 of the present design;

FIG. 10 is a rear view of the embodiment of FIG. 8 of the present design;

FIG. 11 is a right side view of the embodiment of FIG. 8 of the present design;

FIG. 12 is a left side view of the embodiment of FIG. 8 of the present design;

FIG. 13 is a top view of the embodiment of FIG. 8 of the present design; and,

FIG. 14 is a bottom view of the embodiment of FIG. 8 of the present design.

1 Claim, 14 Drawing Sheets
